UNITED STATES PATENT OFFICE

WILLIAM A. RUSSELL, OF YONKERS, NEW YORK, ASSIGNOR TO W. A. RUSSELL & CO.,
OF NEW YORK, N. Y., A CORPORATION OF NEW YORK

AIR VALVE

Application filed April 30, 1927. Serial No. 187,735.

This invention relates to certain improvements in air valves for steam radiators and the like.

Air valves are used with steam radiators 5 to provide communication between the radiator and the outer air, and it is the function of these valves to permit escape of air in the radiator to the atmosphere, the valve closing after the air has been driven out to 10 prevent discharge of the steam through the valve.

In certain types of these valves there is provided a single walled casing having means for attaching it to a radiator in which 15 works a valve body which controls an air vent in the casing. This valve has to be spaced a sufficient distance from the inner walls of the casing to provide for the necessary air circulation. It sometimes happens 20 that with a single wall casing the valve will tip and become jammed so that it cannot function to open and close the air vent, thus rendering the valve inoperative.

It is the especial object of the present invention to improve the construction of these 25 single casing valves by the provision of a guide which will effectually prevent the tipping or tilting of the valve, so that the valve will operate under conditions of use.

It is a further object of the invention to 30 provide a construction which shall be cheap, and not add greatly to the cost of production of the valve.

With these and other objects not specifically referred to, the invention consists in 35 certain novel parts, arrangements and combinations which will be described in connection with the accompanying drawings and the novel features pointed out in the claims 40 hereunto annexed.

In these drawings,—

Figure 1 is a vertical sectional view showing the improved valve positioned on a radiator, and

Figure 2 is a view of the improved guide. Referring now to these drawings, the air valve comprises a single casing 1 formed with a base 2 threaded thereto, the base being provided with a nipple 3 by which it may 50 be threaded into the wall of a radiator 4,

this nipple being secured to the base in any suitable manner. A siphon tube 5 of usual form passes through the nipple connecting the interior of the casing and the radiator.

The upper part of the casing is provided 55 with an air vent formed in a channelled plug 6, preferably for adjustment, threaded in a depending flange 7 conveniently formed by turning in the metal of the casing. The channel 8 of the plug opens to the atmosphere, and the lower end of the channel is widened to form a valve seat 9.

Working within the casing 1 is a valve 10 60 in the form of an elongated hollow body having a nipple 11 for closing the channel 8, the nipple having a coned end 9'. In the particular construction shown, the valve 10 is an expansion valve having a bottom 12 of light metal which will flex under pressure, the valve being filled with a volatile liquid, 70 as alcohol. Where this type of valve is employed, the casing is provided with an abutment in the form of a raised portion 13 formed by bending in the metal of the casing. The upper surface of this abutment 75 is preferably provided with raised portions 14 with openings between to prevent the valve from sticking.

Between the valve 10 and the inner wall 80 of the casing is an air passage 15, this passage being of suitable dimensions to allow free passage of air and steam through the valve, the valve 10 being spaced from the walls of the casing to provide this passage.

In accordance with the invention there is 85 provided a guide of improved construction by which the valve is prevented from tilting and becoming jammed. While the specific construction of this guide may be somewhat varied, it will be so formed and arranged as 90 not to interfere with the free passage of air and steam around the valve. As shown, the base 2 of the valve casing and the lower part of the valve 10 are of somewhat greater diameter than the rest of the parts, and the 95 guide is preferably located above this enlarged part of the valve. The guide shown comprises a ring 16 of light metal suitably secured as by solder to the inner wall of the casing, this ring being provided with spaced 100

projections 17 extending across the air passage 15 and embracing the valve with a loose fit, so that the valve may work freely up and down between the projections. This 5 guide keeps the valve in upright position so that as the valve rises and falls, it does so in substantially a straight line and cannot tilt sufficiently to become jammed. Furthermore, a very simple and inexpensive air 10 valve construction has been provided.

While the invention has been described in what is considered its preferred form, it will be understood that certain variations may be made in the form of the casing, float 15 and guide without departing from the invention as defined in the appended claims.

What I claim is:

In an air valve, the combination of a single-walled casing and means for securing 20 it to a radiator, an elongated valve in the casing spaced from the inner walls thereof to form an air passage, a ring having a vertical flange secured to the inner walls of the casing, projecting lips extending across the air 25 passage, with wide air openings between the projections and freely engaging the valve, and an air vent in the casing controlled by the valve.

In testimony whereof, I have hereunto set 30 my hand.

WILLIAM A. RUSSELL.
